UNITED STATES PATENT OFFICE.

NATHAN LOUIS SHATEN, OF PHILADELPHIA, PENNSYLVANIA.

HEATER AND VENTILATOR FOR AUTOMOBILES.

1,273,006.

Specification of Letters Patent.

Patented July 16, 1918.

Application filed June 12, 1916, Serial No. 103,142.

Renewed February 14, 1918. Serial No. 217,224.

To all whom it may concern:

Be it known that I, NATHAN LOUIS SHATEN, a citizen of the United States, residing at Philadelphia, county of Philadelphia, and State of Pennsylvania, have invented a new and useful Improvement in Heaters and Ventilators for Automobiles, of which the following is a full, clear, and exact description, reference being had to the accompanying drawings, which form a part of this specification.

The object of my invention is to provide a new and improved heater for automobiles, so constructed that the maximum amount of heat may be obtained and also so constructed that, at will, the heater may be used to heat or ventilate the interior of an automobile body.

Other objects of my invention are to provide means whereby the maximum amount of heat, from the engine exhaust, may be extracted without causing any back pressure on the engine, and to so construct the heater that the heat may be divided between various parts of the car body or delivered entirely to any one portion with equal effectiveness.

A further object of my invention is to provide a water jacket about the exhaust pipe, the water being adapted to transmit the heat to the body heating medium, air, and to provide means whereby any pressure in the water jacket will be automatically relieved and the jacket maintained constantly full of water.

A preferred embodiment of my invention is shown in the drawings, in which—

Figure 1 is a side elevation showing my heater, with water supply and pressure relief, attached to an automobile.

Fig. 2 is a plan view of Fig. 1.

Fig. 3 is a longitudinal view in section of the heater.

Fig. 4 is a cross sectional view through the line 4—4, Fig. 3.

Fastened to the chassis *a* is the motor exhaust-pipe *b*. *d* is a worm shaped corrugated pipe having the tubes 15 passing diametrically through its walls, branching off from the main exhaust pipe and having the valve *e* at the point of branching, adapted to permit or prevent the passage of the exhaust through the branch pipe. The branch pipe reunites with the main exhaust pipe

ahead of the conventional muffler *f*. Surrounding the branch pipe *d* is chamber *g* conforming in cross-section to the cross-section of the branch pipe *d*, having communication through the pipe *d* by means of the tubes 15 and adapted to be kept full of water. The valve 14 is provided in the chamber *g* for draining the chamber. Surrounding the chamber *g* is the cylindrical air chamber *h* having the spirals *i* and *i'* running its full length and extending, in width, from contact with the chamber *g* to contact with the outer walls of the chamber *h*. Across the chamber *h* are placed the perforated partitions *j*, *k* and *l* covered by screens and adapted to be partially or wholly closed by the revoluble gates *j'*, *k'*, and *l'*. In the bottom of the chamber *h* are the air inlets *m*, *n*, and *o* protected by the removable screens 10, 11 and 12. The inlets *m* and *o* have the hinged covers *p* while the inlet *n* has the casing *q* depending from it and divided by a downward extension 13 of the partition *k*.

The chamber *h* is suitably connected near its forward end to the radiator *r* and at its rear end to the radiator *s*. In both radiators are suitably disposed the curved partitions *t* adapted to distribute the heat over the entire discharge surface thereof.

The lower portion of the chamber *g* is connected at the forward end to the bottom of the conventional radiator *u* of an automobile, by means of the pipe *v* having therein the check valve *w* permitting water to flow from the radiator into the chamber *g* but not in the reverse direction, and the shut-off valve *x* adapted for use when the heater is not used. The top of the chamber *g* is suitably connected to the top of the radiator *u* by means of the pipe *y* having near the top thereof the relief valve *z* adapted to be set to relieve a predetermined pressure in the chamber *g*.

In practice the chamber *g* is filled with water from the radiator *u* by opening the shut-off valve *x*; the check valve *w* permitting the water to flow into the chamber *g* through the pipe *v*. The water, seeking its own level, will fill the chamber *g* and rise in the pipe *y* to a height corresponding to the water level in the radiator *u*. The covers *p* are closed over the air inlets *m* and *o*, and the valve *e* is set to permit the exhaust

to pass through the branch pipe *d*. The relief valve *z* is set to open at a pressure of one pound, and the gate *k'* is closed. The automobile is now started and operated in the usual manner. The exhaust of the engine passes through the spirally corrugated pipe *a* and heats the water in the chamber *g*.

10 Air enters the air inlet casing *q* and is divided by the downward extension 13 of the partition *k*, part of the air being sent toward the forward end of the chamber *h* and part being sent to the rear thereof. The air passes to the front and rear of the chamber about the spirals *i* and *i'*. The heat of the exhaust is extracted by the water in the chamber *g* and the heat of the water is in turn extracted by the air which is heated in its passage through the chamber *h*.

15 When the air reaches the forward and rear ends of the air chamber it has become thoroughly heated and passes through the screened partitions *j* and *l* into the radiators *r* and *s* respectively, where it is divided by the curved partitions *t* and is evenly distributed into the car body. The air before reaching the car body is thoroughly cleaned by the screen 11 and the screened partitions *j* and *l*.

20 Should a pressure of one pound be developed in the chamber *g* the relief valve *z* will open and the pressure relieved, and steam or water will pass into the engine radiator *u*. As the pressure is relieved a certain amount of water will be lost from the chamber *g* and the level of the water therein will be 25 lower than in the radiator. Hence as soon as the pressure is relieved, the check valve *w* will permit the water to flow from the radiator into the chamber *g* and again come 30 to a level.

35 The chamber *g* is of relatively small capacity and does not materially affect the supply of water in the radiator *u*, necessary for cooling the engine.

40 My invention is capable of a number of variations from the practice above described. For example, if the air from the heater is too hot, it can be cooled before entering the front, or rear portion of the car body, or 45 both by opening one or both of the hinged covers *p* on the air inlets *m* and *o*, thus admitting more or less cold air into the heated air and cooling it.

50 Should it be desired to heat only one portion of the car body, let us say the rear, the gate *j'* at the forward end of the chamber *h* is closed and the gate *k'* opened. Thus all the heated air goes through partition *l'* into the radiator *s*. The front part of the car 55 body can be made to receive all the heat by closing the gate *l'* and opening the gate *k'* and *j'*.

55 If it is desired to use the device as a ventilator, the gates *j'* or *l'*, or both, are closed and the hinged cover *p* on either or both of

the inlets *m* and *o* are opened. It is self-evident that either end of the car body may be ventilated while the opposite end is heated, without disturbing in any way the operation of the heater.

60 During the season when no heat is required the valve *e* may be closed and the exhaust prevented from passing through the heater. The shut-off valve *x* is closed and the water drained from the heater by the valve 14. The entire heater may then be used as a ventilator for the car body and the amount of ventilation controlled in a manner similar to the method of controlling the heat.

65 Having now fully described my invention, what I claim and desire to protect by Letters Patent is—

70 1. In a heater for automobiles, the combination with a gas exhaust pipe, of a water chamber and an air chamber surrounding said pipe, a water reservoir, an inflow pipe connecting the reservoir and the water chamber, a check valve normally closed, but adapted to permit the water, in seeking its 75 level, to flow from the reservoir to the water chamber, an outflow pipe communicating with the water chamber, and an automatic release valve in said outflow pipe, normally closed, but adapted to open to relieve 80 a predetermined pressure in said water chamber.

75 2. In a heater for automobiles, the combination with an automobile water radiator, of a gas exhaust pipe, a water chamber and an air chamber surrounding the pipe, an inflow pipe connecting the lower part of the radiator with the water chamber, a valve in said pipe normally closed, but adapted to open on the lowering of the level of the water in said chamber, an outflow pipe connecting the water chamber with the upper part of the radiator, and a valve in said outflow pipe normally closed, but adapted to open to relieve any excess pressure in the 85 water chamber, there being normally no circulation between the water in the water chamber and that in the radiator.

80 3. In a heater for automobiles, the combination with a gas exhaust pipe of an air chamber surrounding the same having an inlet for atmospheric air at both ends thereof, an outlet at one end of said chamber communicating with a register within the automobile body, and a valve adapted to 115 close the inlet for atmospheric air adjacent the outlet communicating with the register, whereby more or less air may be admitted to the register without its having previously passed through the length of said chamber.

85 4. In a heater for automobiles the combination with a gas exhaust pipe of an air chamber surrounding the same and having an opening for atmospheric air at one part of the chamber, a register communicating 120

with another part of the chamber, a valved opening for atmospheric air at the latter part of the chamber, and a closure adapted to be manipulated to open and close communication between the latter part of the chamber and the remainder thereof, whereby the air admitted through the valved opening will act mainly as a ventilator.

5. In a heater for automobiles, the combination with a gas exhaust pipe of an air chamber surrounding the same and having an opening for atmospheric air at one part of the chamber, a register communicating with another part of the chamber, an orificed partition interposed in the chamber, and a gate adjacent to the partition and

adapted to be operated to more or less open and close the orificed part of said partition.

6. In a heater for automobiles, the combination with a gas exhaust pipe, of a water chamber surrounding said pipe, an air chamber surrounding the water chamber, there being an air inlet and an air outlet at different points along the chamber, a spiral extending longitudinally in the air chamber between the air inlet and the air outlet, and a register communicating with the air outlet.

In testimony of which invention, I have hereunto set my hand, at Philadelphia, on this 29th day of May, 1916.

NATHAN LOUIS SHATEN.
